UNITED STATES PATENT OFFICE.

CHARLES SPENCER, OF HAMILTON, ONTARIO, CANADA.

SANDING DEVICE FOR RAILWAYS AND THE LIKE.

1,404,903.

Specification of Letters Patent. Patented Jan. 31, 1922.

Application filed February 5, 1921. Serial No. 442,769.

To all whom it may concern:

Be it known that I, CHARLES SPENCER, a subject of the King of Great Britain, residing in the city of Hamilton, county of

5 Wentworth, Province of Ontario, Dominion of Canada, have invented certain new and useful Improvements in Sanding Devices for Railways and the like, of which the following is a specification.

10 My invention relates to improvements in sanding devices for railways and the like, and the object of the invention is to devise an apparatus for delivering sand to the rails in which the possibility of clogging of the 15 apparatus is reduced to a minimum, a further object is to prevent waste of the sand and a still further object is to provide an apparatus which will be very accessible in all its parts.

20 My invention consists of an ordinary sand container having an orifice therein, a suction member secured to the container and extending through said orifice, said suction member adapted to draw heated air through 25 the body of sand in the container and also to draw sand from the container, suitable pipes for carrying the sand thus drawn from the container and delivering at the desired point on the rails, all as herein- 30 after more particularly described in the accompanying drawings in which,

Fig. 1 is a central vertical section showing my invention, the sand container being shown broken away to economize space, 35 also one of the shoes broken intermediately for the same purpose.

Fig. 2 is a cross section on the line 2, 2 of Fig. 1.

Fig. 3 is a plan view showing the form 40 of the end of one of the sand delivering pipes used in my invention.

Fig. 4 is a section on the line 4, 4 of Fig. 3, looking in the direction of the arrow.

Fig. 5 is a perspective detail showing the 45 form of the end of a spring used in supporting the dome.

Fig. 6 is a cross section on the line 6, 6 of Fig. 1.

Like characters of reference indicate corresponding parts in the different views. 50

1 is the sand container which has an orifice 2 in the bottom thereof.

3 is a suction member comprising the main tubular body portion 4 having an axial passageway 5 therein. 55

This passageway 5 is funnel shaped at its upper end at 6. Directly below the funnel shaped portion 6 is a cylindrical portion 7. Immediately below the portion 7, the bore of the passageway 5 is increased 60 at 8 and from this enlargement the walls converge to form a tapered portion 9, at the lower end of which a waist is formed at 10, the diameter at the waist being only slightly greater than that of the cylindrical portion 7. 65

From the waist 10 the suction member terminates in two Y-branches 11 which are threaded at 12 to receive the delivering pipes 13. 70

14 is an enlarged head formed on the member 3 and comprises the depending annular flange 15 and the upper inclined face 16. This head 14 constitutes a suction head within the sand container. 75

The suction member 3 is connected to the sand container 1 so that the annular flange 15 extends upwardly through the orifice 2 and is secured by bolts 17 extending through orifices in a flange 18 and having threaded 80 engagement in orifices in the bottom of the container 1. 19 are spring washers locking the screws 17.

The junction of the wall 20 of the annular flange 15 with the inclined face 16 is 85 rounded as at 21.

22 is an open ended tube having the bore 23 and fits tightly into the cylindrical portion 7 of the member 3.

This tube extends downwardly and has 90 its lower extremity located adjacent to the waist 10. Between this tube and the walls 9 is formed a tapered annular chamber 91.

24 is a circular dome which is supported above the head 14 by the spring strips 25. 95

The inner ends of these spring strips 25

are hooked at 26 (see Fig. 5) to receive the lower part of the dome.

The inner ends of the strips 25 are secured to the inclined face 16 of the head 5 14 by the screws 27.

In mounting the dome 24 the lower edge thereof engages the hooks 26 of the strips 25 and it is secured by screws 29 which engage orifices 30 in the dome. These orifices 30 are larger than the screws 29 so that the dome is not rigidly secured but is free to move up and down slightly, due to the play of the screws 29 within the orifices 30.

15 The spring strips 25 are so shaped that they form a resilient support for the dome 24.

31 is a threaded plug engaging an orifice 32 in the member 3 located between the Y 20 branches 11 and centrally opposite the end of the tube 22.

33 is a boss carried at one side of the member 3 and having a passage 34 extending therethrough and communicating with the upper portion of the tapered annular passage 9¹. The outer end of the passage 34 is inclined slightly downward for convenience in assembling the apparatus and is threaded to receive the compressed air 25 supply pipe 35. 35¹ is a valve for controlling the supply of compressed air and is operated by the connection 35² leading to the control station of the car.

The two pipes 13 connected to the 35 branches 11 lead laterally and are connected at 36 to pipes 37.

Since only the connections leading from the left hand branch 11 have been illustrated, the description will be confined to 40 this side only but it will of course be understood that the right hand branch will comprise identical parts.

The pipe 37 has a cut away portion 38 adjacent to its outer end (see left of Fig. 1), 45 the outer edge of this cut away portion being provided with notches 39 for a purpose as will presently appear.

The pipe 37 is further provided with an orifice 40 located diametrically opposite to 50 the cut away portion 38.

41 is a shoe consisting of a pipe closed at its upper end and tapered laterally at its lower end to form a narrow elongated slot 42 extending parallel to the rail 43.

55 Near the upper end of the shoe 41 it is provided with an orifice 44 adapted to receive the end of the pipe 37 for detachably mounting the shoe upon the pipe.

Diametrically opposite the orifice 44 the 60 shoe has a further smaller orifice 45.

46 is a securing finger which carries the inner nut 47 at its outer end and has its inner end formed into the hook 48. The shank of the finger carries the coil spring 65 49 and the washer 50.

The inner end of the finger is adapted to extend through the orifice 45 and to engage the notches 39 in the pipe 37 for securing the shoe 41 in place on the pipe 37.

The lengths of the pipe 37 and of the 70 shoe 41 are so arranged that the slot 42 is located in the desired position directly above the rail.

The pipe 37 is provided with a number of notches 39 for a purpose as will herein- 75 after appear.

51 is a suction whistle and 52 is a pipe leading from this whistle into proximity to the suction head 14.

53 (see Fig. 1) indicates any heating element located at the top of the sand container.

The construction and operation of my device is as follows:

Considering the container 1 to be full of 85 sand, the weight of the sand above the dome 24 will cause the level of the sand under the dome, to rise slightly above the bottom edge thereof and the sand will thus follow slightly up the inclined face 16 of the 90 head 14.

Now suppose the valve 35¹ is opened admitting compressed air to the tapered annular chamber 9¹.

This compressed air will rush downwardly 95 through the chamber 9¹ and due to the shape of this chamber the velocity will increase and the pressure will decrease until when it passes the waist 10 through the extremely narrow annular opening between the tube 100 22 and the waist 10, the velocity will be very high with the result that a powerful vacuum will be produced directly at the lower end of the passage 23 at the point A. (See Fig. 1.)

105 This vacuum will produce a suction under the dome 24 and sand will be drawn into the funnel 6 and downwardly through the passage 23. As soon as the sand emerges from the lower end of the passage 23, it will be carried by the air from the chamber 9¹ outwardly through the branches 11 to the shoes 41.

It will be evident that in addition to the sand being drawn into the suction member 115 that air will also be drawn downwardly through the body of sand in the container.

If now some provision, such as a heating element 53, be made for heating this air before it enters the container, it will be evident that whenever the apparatus is operated, a current of heated air will be drawn through the body of sand in the container and thus remove objectionable moisture therefrom.

125 When the apparatus is operating the suction under the dome 24 will draw same downwardly against the pressure of the spring strips 25, but as soon as the compressed air is shut off the suction will dis-

appear and thus the springs will tend to raise the dome.

If therefore the compressed air valve 35¹ be operated with an intermittance action, 5 which will be the case in practice, the dome will have a slight vibrating motion which will aid the flow of sand. In order to increase this vibrating effect the holes 30 are made larger than the screws 29 so that the 10 dome is not rigidly mounted on the springs 25.

The suction whistle 51 will sound whenever the vacuum is produced and will be a signal to the operator indicating the condition of the apparatus. 15

The valve 35¹ would of course be connected in a suitable manner so that it could be operated by the motorman from his control station. This connection is indicated 20 diagrammatically at 35².

It will be seen that the apparatus described constitutes what might be termed a suction head within the sand container, the action of which is to draw sand from the container 25 and also to draw heated air from outside through the body of the sand towards the suction head.

The method of delivering the sand from the suction member to the rails will now be 30 described.

As already stated the branches 11 lead laterally towards each rail.

In order to mount the detachable shoe 41 it is simply placed so that the end of the 35 pipe 37 extends through the orifice 44 in the shoe. The shoe is secured in place by engaging the hook 48 of the finger 46 in one of the notches 39. The coil spring 49 prevents disengagement.

40 The shape and length of the pipes are so arranged that in this position the slot 42 of the shoe is in the desired position over the rail 43.

Since it is desirable that the sand be deposited quietly upon the rail and not blown thereon, it is desirable to remove the force 45 of the current of air which carries the sand from the bottom of the suction tube 22 to the pipes 37.

50 This is accomplished in my invention by the peculiar construction of the shoe 41 and outlet of the pipe 37.

The cut away portion 38 is located on the upper side of the pipe 37 so that the air as it 55 enters the shoe is deflected upwardly against the top and then again deflected downwardly.

The path of the sand will be much the same as that of the air, some will be deflected upwardly through the cut away portion 60 38 while some will strike against the outer wall of the shoe.

In either case the course of the sand is changed and all velocity which it had in the pipes 13 and 37 is eliminated.

Further the shoe 41 is of considerably 65 greater diameter than the pipe 37 which will allow expansion and further reduce the force of the current of air.

In this way the sand will drop freely onto the rail by gravity and will not be blown 70 thereonto.

If desired an orifice 40 might be provided on the under face of the pipe 37.

In order to permit a certain amount of flexibility and adjustment, a number of 75 notches 39 are provided to allow the cut away portion 38 of the pipe 37 to be placed in various inclined positions. This will be clearly followed from Figures 3 and 4, the straight pipe 37 being turned at the joint 80 36 to effect the adjustment.

To provide for ease and convenience in cleaning and in assembling, the large plug 31 is fitted at the Y-branch. When this is removed it provides a clear unobstructed 85 straight passage through the member 3.

The assembling and adjustments of the shoe 41 are very conveniently accomplished since, to remove the shoe it is only necessary to depress and turn the finger 46. 90

In this way the shoe can be easily removed so as to be out of the way of the workmen engaged on the under carriage or to provide clearance in case of snow or such like.

Hitherto one of the great difficulties experienced in the use of sanding devices has been the clogging of the sand, with the result that the flow of sand is interfered with or entirely stopped. 95

This has been due to the sand becoming 100 moist and sticky and in cold weather freezing, into a more or less solid mass in the container.

These weaknesses were, of course, present in the ordinary gravity feed type and with 105 a view of improving the flow of the sand various types using compressed air were developed.

These comprised an air nozzle within the sand container disposed in proximity to the 110 opening of the sand pipe leading from the container to the rails. The sand in the container was packed about the nozzle and pipe opening and when compressed air was turned on it rushed from the nozzle into the 115 sand pipe and carried with it the surrounding sand which was thus blown through the usual pipes to the rails.

In this system the compressed air, which always contains a considerable degree of 120 moisture came into direct contact with the body of sand in the container, with the result that this body of sand became damp and in cold weather would freeze thus rendering the apparatus inoperative, since the 125 sand was not sufficiently loose to flow into the pipe.

It is with a view of overcoming these diffi-

culties formerly experienced, that my improved apparatus has been devised.

It will be seen that in my apparatus the moist compressed air does not ever come 5 in contact with the sand in the container, but in fact does not meet the sand until the latter emerges from the lower end of the tube 23 and enters the large pipes 11 after which point there is no possibility of clog- 10 ging.

Further whenever the device is operated, a current of heated air is drawn through the body of sand in the container, so that all 15 moisture is removed from the sand and there is no possibility of freezing.

Further since the air valve 35¹ is to be operated with an intermittent action, the current of heated air will be drawn through the sand in the container in pulsations and 20 not continuously which will further prevent caking of the sand and keep it loosely packed and in a proper condition to be drawn into the suction head 14. Also the slight rise and fall of the dome will assist 25 this action.

Apart from the effect of the compressed air moistening the sand in the container, in former devices where the sand simply lies 30 in a container exposed to the atmosphere, it naturally becomes moist with the aforementioned undesirable results.

In my apparatus this is not the case, as the sand is not exposed to the ordinary atmospheric conditions but is continually being dried.

It will be noticed that in my apparatus no leakage of sand from the container can take place as the sand cannot possibly flow except when drawn up into the tube 23 by 40 suction.

While I have illustrated and described one form in which my invention may be made, it is to be understood that various modifications could be made without departing 45 from the spirit of the invention or the scope of the claims and the form shown is to be taken as illustrative only and not in a limiting sense.

For instance, the heating element 53 shown in Fig. 1, is diagrammatic only to indicate any means of heating the air entering the sand container. This could be accomplished by arranging the top of the container in communication with the ordinary 55 warm air in the car so that as the apparatus was operated the warm air from the car would be drawn through the sand container.

Also while I have shown a separate tube 22 fitted into the member 3, it might be possible or desirable that this would be constructed integrally with the member 3 all in one casting.

Further while I have described particularly the use of compressed air, my apparatus 65 could also be operated by steam in which

case the action would be the same as that already described. The advantage in this case over former types would be even more marked since the steam would have more tendency to moisten the sand in these former devices whereas in mine there would still be no moistening effect on the sand in the container.

Again while I have shown my apparatus as fitted to the bottom of the sand container, 70 it could, with slight obvious modifications, be fitted in any desired position thereto.

From the foregoing it will be seen that I have devised an improved sanding device for use on street cars, railways and the like which will be very reliable in operation, which will not be affected by climatic conditions and in which no waste of sand can occur.

What I claim as my invention is:

1. In a sanding device for railways and the like, the combination with the sand container and the sand therein, of suction means for withdrawing sand from the container and for drawing a current of heated air through the body of sand in the container.

2. In a sanding device for railways and the like, the combination with the sand container and the sand therein, of a suction member carried by the container, said member comprising an open ended tubular portion communicating with the container, the suction member having an annular chamber surrounding the outer part of said tubular portion, said annular chamber being closed at its inner end and open at its outer end, means for admitting a pressure fluid to the inner end of the annular chamber, said pressure fluid rushing outwardly through the chamber and creating a vacuum at the open outer end of the tubular portion.

3. In a sanding device for railways and the like, the combination with the sand container and the sand therein, of a suction member carried by the container, said member comprising an open ended tubular portion, communicating with the container, the suction member having an annular chamber surrounding the outer part of said tubular portion and being closed at its inner end and tapering towards its outer end to form a narrow annular nozzle about the open outer end of the aforesaid tubular portion.

4. In a sanding device for railways and the like, the combination with the sand container and the sand therein, of a suction member carried by the container, said member comprising an open ended tubular portion, communicating with the container, the suction member having an annular chamber surrounding the outer part of said tubular portion and being closed at its inner end and tapering towards its outer end to form a narrow annular nozzle about the

open outer end of the aforesaid tubular portion and means for admitting a pressure fluid to the upper end of the annular chamber.

5. In a sanding device for railways and the like, the combination with the sand container and the sand therein, of an open ended tubular member communicating with the container, a baffle plate supported within the container over the open inner end of the tubular member and in spaced relation thereto and means for producing a vacuum at the outer end of said tubular member whereby the contents of the container are drawn outwardly through the tubular member.

6. In a sanding device for railways and the like, the combination with the sand container and the sand therein, of an open ended tubular member communicating with the container, a dome shaped baffle member resiliently supported within the container over the open inner end of the tubular member and in spaced relation thereto and means for producing a vacuum at the outer end of said tubular member whereby the contents of the container are drawn outwardly through the tubular member.

7. In a sanding device for railways and the like, the combination with the sand container and the sand therein, of a suction member secured to the container, said suction member comprising a flanged head extending into the container, an open ended tubular portion extending longitudinally into the suction member from the inner end thereof, the suction member having an annular chamber, surrounding the outer part of the tubular portion and being closed at its inner end and tapering towards its outer end to form a narrow annular nozzle about the open outer end of the tubular portion, a transverse passageway in the suction member communicating with the enlarged upper end of the annular chamber and a compressed air supply pipe engaging the outer end of said passageway.

8. In a sanding device for railways and the like, the combination with the sand container and the sand therein, of a suction member secured to the container, said suction member comprising a flanged head extending into the container, an open ended tubular portion extending longitudinally into the suction member from the inner end thereof, the suction member having an annular chamber, surrounding the outer part of the tubular portion and being closed at its inner end and tapering towards its outer end to form a narrow annular nozzle about the open outer end of the tubular portion, a passageway in the suction member communicating with the upper enlarged end of the annular chamber for admitting a pressure fluid thereto and a baffle member sup-

ported within the container over the head of the suction member and in spaced relation thereto.

9. In a sanding device for railways and the like, the combination with the sand container and the sand therein, of a suction member secured to the container, said suction member comprising a flanged head extending into the container, an open ended tubular portion extending longitudinally into the suction member from the inner end thereof, the suction member having an annular chamber surrounding the outer part of the tubular portion and being closed at its inner end and tapering towards its outer end to form a narrow annular nozzle about the open outer end of the tubular portion, a passageway in the suction member communicating with the upper enlarged end of the annular chamber for admitting a pressure fluid thereto and a dome shaped member resiliently supported within the container over the head of the suction member and in spaced relation thereto.

10. In a sanding device for railways and the like, the combination with the sand container, and the sand therein, of a suction member secured to the container, said suction member comprising a flanged head extending into the container, an open ended tubular portion extending longitudinally into the suction member from the inner end thereof, the suction member having an annular chamber surrounding the outer part of the tubular portion and being closed at its inner end and tapering towards its outer end to form a narrow annular nozzle about the open outer end of the tubular portion, a passageway in the suction member communicating with the upper enlarged end of the annular chamber for admitting a pressure fluid thereto, a dome shaped member resiliently supported within the container over the head of the suction member and in spaced relation thereto, and means for imparting a vibrating motion to the dome shaped member.

11. In a sanding device for railways and the like, the combination with the sand container and the sand therein, of a suction member secured to the container, said suction member comprising a flanged head extending into the container, an open ended tubular portion extending longitudinally into the suction member from the inner end thereof, the suction member having an annular chamber surrounding the outer part of the tubular portion and being closed at its inner end and tapering towards its outer end to form a narrow annular nozzle about the open outer end of the tubular portion, a passageway in the suction member communicating with the upper enlarged end of the annular chamber for admitting a pressure fluid thereto and a dome shaped mem-

ber resiliently supported within the container over the head of the suction member and in spaced relation thereto and an air heating means engaging the air before its entry into the sand container.

12. In a sanding device for railways and the like, the combination with the sand container and the sand therein, of a suction head communicating with the container, 10 means for producing a suction at the suction head whereby sand is drawn from the container into the suction head and a signal operated by the suction.

13. In a sanding device for railways and 15 the like, the combination with the sand container and the sand therein, of a suction head communicating with the container, means for producing a suction at the suction head whereby sand is drawn from the 20 container into the suction head, and a suction whistle actuated by the suction at the suction head.

14. In a sanding device for railways and 25 the like, the combination with the sand container and the sand therein, of a suction member secured to the container, said suction member comprising a flanged head extending into the container, an open ended tubular portion extending longitudinally 30 into the suction member from the inner end thereof, the suction member having an annular chamber surrounding the outer part of the tubular portion and being closed at its inner end and tapering towards its outer 35 end to form a narrow annular nozzle about the open outer end of the tubular portion, a passageway in the suction member communicating with the upper enlarged end of the annular chamber for admitting a pressure 40 fluid thereinto, a dome shaped member resiliently supported within the container over the head of the suction member and in spaced relation thereto and means for intermittently admitting the pressure fluid to the 45 annular chamber.

15. In a sanding device for railways and 50 the like, the combination with the sand container and the sand therein, of a suction member secured to the bottom of the container, said suction member comprising a flanged head extending upwardly into the container, an open ended tubular portion extending longitudinally into the suction member from the inner end thereof, the suction 55 member having an annular chamber surrounding the outer part of the tubular portion and being closed at its inner end and tapering towards its outer end to form a narrow annular nozzle about the open outer 60 end of the tubular portion, a passageway in the suction member communicating with the upper enlarged end of the annular chamber for admitting a pressure fluid thereinto, and a dome shaped member resiliently supported 65 within the container over the head of the

suction member and in spaced relation thereto.

16. In a device of the class described, a suction member comprising an inverted Y-shaped body having axial communicating 70 passageways extending through the central and side branches thereof, a flanged head on the central branch having the end face thereof inclined, an open ended tubular portion in the central branch, the walls of the passage 75 in this branch being so formed as to constitute an annular chamber closed at its upper end and tapering towards its lower end and forming a narrow annular nozzle about the open lower end of the tubular portion, a 80 transverse passage in the central branch communicating with the upper end of the tapered annular chamber and an air supply pipe connected to the outer end of said transverse passage.

17. In a device of the class described, a suction member comprising an inverted Y-shaped body having axial communicating passageways extending through the central and side branches thereof, a flanged head on 90 the central branch having the end face thereof inclined, an open ended tubular portion in the central branch, the lower end of said tubular portion located approximately at the base of the Y-branches, the walls of the passage in this branch being so formed as to constitute an annular chamber closed at its 95 upper end and tapering towards its lower end and forming a narrow annular nozzle about the open lower end of the tubular portion, a transverse passage in the central branch communicating with the upper end of the tapered annular chamber and an air supply pipe connected to the outer end of said transverse passage.

18. In a sanding device for railways and the like, the combination with the rails, the sand container, the sand therein and the sand delivery pipe leading from the container, of a shoe detachably connected to the outer end 100 of said pipe and adapted to receive the sand therefrom, said shoe comprising a pipe closed at its upper end and having its lower end formed into an elongated narrow slot disposed vertically above and parallel to the 105 rail.

19. In a sanding device for railways and the like, the combination with the sand container, the sand therein, the rails and the sand conveying system between the container and rails, of a detachably mounted shoe located above each rail and adapted to deposit the sand thereon, said shoes each having a narrow elongated slot disposed 120 parallel to and directly above the rail.

20. In a sanding device for railways and the like, the combination with the sand container, sand therein, and the delivery pipes leading from the container, of a current of air passing outwardly through said delivery 130

pipes and baffle means within said pipes for deflecting the current of air to reduce its velocity to a minimum at its point of exit from said pipes.

- 5 21. In a device of the class described, the combination with the sand delivery pipe and the rail, of a detachably mounted shoe having a narrow elongated slot disposed vertically above and parallel to the rail.
- 10 22. In a sanding device for railways and the like, the combination with the sand container and the sand delivery pipes leading therefrom, of a substantially horizontal portion at the outer end of each pipe, a portion 15 of the upper face of said horizontal portion being cut away and a tubular shoe having an orifice in the side thereof, the aforesaid horizontal outer end of the pipe extending through said orifice into the shoe.
- 20 23. In a sanding device for railways and the like, the combination with the sand container and the sand delivery pipes leading therefrom, of a substantially horizontal portion at the outer end of each pipe, a portion 25 of the upper face of said horizontal portion
- being cut away and a tubular shoe having an orifice in the side thereof, the aforesaid horizontal outer end of the pipe extending 30 through said orifice into the shoe, and a clamping means for detachably securing the shoe in position on the pipe.
24. In a sanding device for railways and the like, the combination with the sand container and the sand delivery pipes leading therefrom, of a substantially horizontal portion 35 at the outer end of each pipe, a portion of the upper face of said horizontal portion being cut away and a tubular shoe having an orifice in the side thereof, the aforesaid horizontal outer end of the pipe extending 40 through said orifice into the shoe and a clamping means for detachably securing the shoe in position on the pipe and adapted to be turned so that the cut away portion may be adjusted to various angular positions.

CHARLES SPENCER.
